HOSIERY AND METHOD OF MANUFACTURING THE SAME

Joseph L. Beers, Bloomfield, N. J., assignor to
Julius Kayser & Co., Brooklyn, N. Y.

Application December 5, 1939, Serial No. 307,608

31 Claims. (Cl. 66—187)

The present invention relates to hosiery, more particularly to full-fashioned stockings manufactured in accordance with certain features of the method set forth in my co-pending application, Serial Number 106,828, filed October 21, 1936, of which the present application is a continuation in part.

An important object of the invention resides in the provision of a method whereby are eliminated certain looping operations which have heretofore been necessary to join certain parts of the stocking. According to the present invention, these parts are joined during the knitting operation.

It is also an important object of the invention to provide a stocking blank wherein the usual relatively wide, bulging, and unsightly looping seams at the heel and foot sections are obviated, and narrow, flat seams of smooth, even appearance are formed therein.

The invention moreover is characterized particularly by the provision of a stocking wherein, and a method whereby, the free loops at the tip of the toe portion, as well as the free loops at the bottom portion of the heel tabs are united by knitting relatively narrow strips of fabric on a knitting machine and, during the knitting of such strips, interknitting therewith said free loops, accordingly producing a stocking without connections requiring extra looping operations at said portions.

It is also one of the characteristic features of the invention to provide a stocking of the type mentioned wherein the heel tabs are knitted directly onto, and as continuations of, the high heel portions of a combination leg and foot blank, and the sole portions of said blank are interknitted with the heel tabs as the knitting thereof progresses, and the normally free loops at the bottom of the heel tabs and/or at the tip of the toe are united by means of a knitted strip with which said normally free loops are interknitted during the knitting of said strip.

Other important objects and advantages of the invention will be in part obvious and in part pointed out hereinafter.

In order that the invention may be readily understood by those skilled in the art, I have, in the accompanying drawings and in the detailed description based thereupon, set out a possible embodiment of the invention.

In these drawings:

Figure 1 is a perspective of a completed stocking constructed in accordance with the invention;

Figure 2 is an elevation on a reduced scale of a combination leg and foot blank from which the stocking shown in Figure 1 is made;

Figure 3 represents the blank of Figure 2 with the heel tabs knitted therein;

Figure 4 is an enlarged view of the blank shown in Figure 3 with the bottom edges of the heel tabs and the tip of the toe united by means of knitted strips;

10 Figure 5 diagrammatically shows a portion of the blank represented in Figure 2 severed and folded for engagement with the needles of a knitting machine intended to knit heel tabs onto, and as continuations of, the high heel sections of the blank;

Figure 6 diagrammatically shows the engagement of loops with sets of knitting and non-knitting needles;

20 Figure 7 diagrammatically illustrates the mode of transferring loops of the foot portion for interknitting engagement with the heel tabs as the knitting thereof progresses;

Figures 8 and 9 show the mode of uniting the edges of the heel tabs;

25 Figure 10 diagrammatically illustrates the transfer of the edge loops at the bottom of the heel tabs;

Figures 11 to 14 inclusive diagrammatically show the mode of uniting the edges at the tip of the toe.

Having more particular reference to the drawings, wherein like characters of reference will designate corresponding parts throughout, I have shown in Figure 1 the completed stocking 1, including the welt 2, the leg 3, the high heel sections 4, the heel tabs 5, the instep 6, the sole sections 7, and the toe 8. In carrying out my improved method, the stocking 1 is preferably made from a blank, such as shown in Figure 2, wherein the welt 2, the leg 3, with the high heel sections 4, the instep 6, and sole sections 7, and toe 8 are knitted contiguously on one machine. The high heel sections 4, together with the sole sections 7 and toe 8, may be reinforced by introducing additional yarns in the usual manner.

At the point between the high heel sections 4 of the leg 3 and the sole sections 7 of the foot, where the blank is to be severed for the insertion of the heel tabs, there is knitted series of partial loose courses 10 which extend from the selvedge edges for a predetermined distance into the body of the blank, the length of the partial loose courses depending upon the desired width of the heel tabs to be inserted in the fabric.

The provision of the partial loose courses 10, it will be understood, affords a convenient guiding line for the severing of the fabric and, for that purpose, the feed of the additional reinforced yarn is preferably stopped during the formation of said partial loose courses. Subsequent to the separation of the fabric as stated, the foot portion is folded over the leg portion, and the sole sections 1 are folded upon the instep section 6 in the manner more clearly represented in Figure 5 of the drawings. By folding the stocking blank in the manner specified, it will be appreciated that the marginal rows of loops 12 of each of the high heel sections 4 and the marginal row of loops 13 of each of the sole sections 1 lay on a straight line, as indicated at 14, so that said rows of loops 12 and 13 may be topped on the bank of needles of a knitting machine intended to knit the heel tabs.

It is to be noted that, because of the folding of the blank as above set forth, the loops of the foot and sole sections are reversed so that, in the topping operation, the sinker portion of the marginal row of loops 13 of each sole section 1 will engage the corresponding needles of the heel tab knitting machine, whereas the needle portion of the marginal row of loops 12 of each high heel section 4 will engage the associated needles of said heel tab knitting machine, in the manner more clearly represented in Figure 6 of the drawings.

The heel tab knitting machine is provided with two sets of needles diagrammatically shown in Figures 6 and 7, one set of needles 15 being non-knitting needles, the other set of needles 16 being adapted to knit in the usual way. As shown, the non-knitting needles 15 preferably consist of needles having shortened beards, which prevent the loops 13 on said needles from being pressed off during the knitting of the heel tabs 5. It is also possible to use ordinary knitting needles instead of the shortened beard needles and, in this event, the usual presser edge, which is disposed opposite said needles, may be removed so that the needles will not press off, or the needles may be so mounted as to be moved away from their associated presser edge, which will likewise prevent pressing off.

Associated with the non-knitting needles 15 are transfer points 17 devised to pick the loops 13 off said non-knitting needles 15 and transfer said loops for interlooping engagement with the adjacent end loops 18 of the courses 19 constituting the heel tabs 5 as the same are being knitted.

The loops 13 on the non-knitting needles 15 are transferred the distance of one or more wales, as necessity or preference may dictate. In Figure 7, I have illustrated the single wale transfer. According to this mode of operation of knitting the heel tabs 5 and simultaneously joining the sole portions 1 thereto, the transfer points 17 descend and pick all of the loops 13 off the non-knitting needles 15 and transfer said loops one needle distance, which places each end loop successively in engagement with the end knitting needle of the row of needles 16. An intermediate course 20 may be knitted on the needles 16 between each transfer operation to provide the necessary fabric for the formation of the heel and to insure sufficient elasticity in the foot. This operation is repeated until all the loops 13 on the non-knitting needles 15 have been transferred the distance of one needle at a time and interknitted to form a seam 21 uniting the sole portions 1 to the heel tabs 5.

The transfer operation causes the marginal loops of the sole sections 1 to become interlooped with the adjacent marginal loops of the heel tabs 5 and, accordingly, no seaming operation is necessary to unite the same. Furthermore, due to the transfer of the loops in the manner specified, the foot fabric is turned automatically at substantially right angles so that the finished blank assumes the proper shape to fit the foot of the wearer.

As stated, the invention contemplates uniting certain parts of the blank by interknitting said parts. In Figures 8, 9, and 10, I have shown the manner in which the heel tabs may be interknitted at their lower marginal edges 22. According to this feature of the invention, after the completion of the heel tabs 5, the blank is folded upon itself to bring said lower edges of the heel tabs adjacent one another so that the marginal row of loops 23 of each heel tab edge 22 may be engaged respectively on two relatively spaced sets of non-knitting needles 24 and 25. Arranged between the spaced sets of non-knitting needles 24 and 25 is a set of knitting needles 26, preferably two in number, although this number may be increased if desired. A yarn 27 is adapted to be suitably fed to the knitting needles 26 in order that short courses 28 forming a strip may be knitted therefrom.

Associated with each set of non-knitting needles 24 and 25 are sets of narrowing points 29 and 30 respectively disposed to engage the rows of loops 23 and progressively transfer them in the manner set forth in the description of the knitting of the heel tabs, whereby the end loop of each row will become interlooped with the adjacent loops of the partial courses 28, as more clearly shown in Figure 10 of the drawings.

It will be understood that the toe section of the foot at the point 31 (Figure 1) may be joined in the same manner as the lower edges of the heel tabs, and in Figures 11 to 14, I have shown how this can be accomplished. As represented in these figures, the adjoining portions, for instance, those portions 32 and 33 of the marginal course at one side of the toe fabric, are engaged respectively on the two relatively spaced sets of non-knitting needles 24 and 25 (Figure 12), whereupon the yarn 27 (Figure 14) is fed to the knitting needles 26 in order to knit short courses, the sets of narrowing points 29 and 30 operating to engage the rows of loops at said portions 32 and 33 and progressively transfer said loops for interknitting connection with the adjacent loops of said partial courses during the knitting thereof. Likewise, the remaining adjoining portions 34 and 35 of the marginal course at the other side of the toe fabric are engaged respectively on the two relatively spaced sets of non-knitting needles 24 and 25 (Figure 13) and yarn is fed to the knitting needles 26 for the knitting of short courses, the sets of narrowing points 29 and 30 again operating to engage the rows of loops at said portions 34 and 35, and progressively transfer said loops for interknitting connection with the adjacent loops of said short courses during the knitting thereof. In this manner, there is produced an interknitting seam between the toe portions 32-33 and 34-35 as indicated at 36 and 37 in Figures 1 and 4, having the same overlapping interknitted construction as the seam at the bottom of the heel tabs, more fully shown in Figure 10.

Of course, it will be understood that the toe

and heel constructions, by means of the knitted strips, may also be used with the so-called "two machine" stocking method, in which a stocking leg blank including the leg, high heel sections, and heel tabs, is made in one operation on a first machine, and then transferred to a second machine for the knitting of a foot blank, including the instep, sole, and toe portions.

It is pointed out that the transfer of the loops from the inactive or non-knitting needles 12-13 or 24-25 to the active or knitting needles 15 and 26 produces a strong and flat seam because, in the manner clearly shown in Figures 7 and 14, the transferred loops from said non-knitting needles are placed in overlapping relation with the needle loops of certain successive courses being knitted on the knitting needles, a needle loop of the next successive course thus passing through the overlapped loops of the preceding course so that said overlapped loops become engaged with the sinker loops of said successive course.

After the completion of the blank, as shown in Figure 4, the free selvedges 38 thereof may be seamed together as is customary to constitute the back seam 39, and the sole seam 40 (Figure 1), thus forming a complete stocking.

I wish it to be understood that the stocking construction and the method of forming the blank therefor may slightly vary without departing from the spirit of the invention. Accordingly, those modifications coming within the scope of the following claims are to be considered within the spirit of the invention.

What I claim is:

1. A full-fashioned knitted stocking comprising a leg fabric, a foot fabric, high and low heel fabrics, and sole fabrics, needle loops of the low heel fabrics being interknitted with sinker loops of the sole fabrics, and the open edge of the low heel fabrics interknitted together to close the heel.

2. A full-fashioned knitted stocking comprising a leg fabric, a foot fabric, heel fabrics, and sole fabrics, certain loops of the heel fabrics being interknitted with certain loops of the sole fabrics, and the terminal course of one of said heel fabrics being interknitted with the terminal course of the other heel fabric.

3. A stocking consisting of a combination leg fabric and foot fabric, heel tabs knitted into said blank and having loops arranged in overlapping relationship with loops of the foot fabric, said loops of the heel tabs passing completely through the overlapping loops and interknitting the same, and the terminal courses of said heel tabs being interknitted.

4. A full-fashioned stocking formed from a blank having heel tab portions terminating in free loops and at least a substantial part of the other edges of the stocking provided with a selvage, the said stocking having the terminal loop edges of said heel tab portions joined together by yarn interknitted with said terminal loops.

5. In a full-fashioned stocking, a heel structure comprising two fabric portions, each portion having a plurality of wales extending to the end edge thereof and each of said wales terminating in an end loop, said fabric portions being joined together by a yarn interknitted with said terminal wale loops to provide a seam for said edges, said seam consisting of yarn having regular courses and wales with the wales running lengthwise of said seam and interknit with said terminal wale loops.

6. A full-fashioned stocking formed from a blank having foot portions terminating in free loops, the said stocking having said foot portions joined together by yarn knitted into a strip with selvedge portions interknitted with said loops.

7. A full-fashioned, machine-knitted stocking, having two groups of terminal wale loops seamed together by knitted yarn, the said knitted yarn having its wales extending substantially at right angles to the wales having said terminal loops.

8. A full-fashioned, machine-knitted stocking made from a blank having both selvedge edges and edges formed of free terminal wale loops, the said stocking having the selvedge edges sewed together to form a stocking seam or seams, and the said terminal loop edges joined together by yarn knitted into a strip with selvedge portions interknit with said terminal wale loops.

9. A full-fashioned, machine-knitted stocking, made from a blank having both selvedge and edges formed of free terminal wale loops, the said stocking having its terminal wale loop edges joined by yarn knitted into a plurality of courses and wales with certain wales interknit with said terminal wale loops.

10. Knitted fabric having a knitted seam, the knitted fabric having edge portions formed of loops, and said seam comprising knitted yarn having regular courses and wales with the wales running lengthwise of said seam and interknit with said edge loops.

11. In knitted hosiery, fabric portions each having an edge formed of terminal wale loops, and knitted yarn joining the loops of one of said portions to the loops of another of said portions, at least a substantial part of said knitted yarn having regular courses and wales with the wales parallel to said edge and interknit with said edge loops.

12. A stocking having edge portions and yarn knitted into loops and interlooped with said edge portions to form a seam therefor, each of at least a substantial number of said yarn loops being interlooped with one and one only of said edge portions.

13. A full-fashioned knitted stocking having terminal loops of certain of its portions interknitted with terminal loops of certain other of its portions, and the selvedge edges thereof seamed.

14. A full-fashioned knitted stocking having terminal loops of certain of its portions interknitted with a separate thread to terminal loops of certain other of its portions, and a seaming thread interconnecting the selvedge edges of the stocking.

15. In a stocking, a structure comprising knitted fabric having portions relatively disposed to provide two adjacent rows of terminal wale loops, said fabric portions being seamed together by yarn knitted into a strip of regular courses of wales, the selvedge loops of which are interknit with said terminal wales loops.

16. Full-fashioned hosiery having knitted portions, each formed of wales terminating in free loops at the end edge thereof, the free loops at one of said end edge portions being seamed to the free loops at another of said end edge portions, the seam for said end edge portions comprising narrow knitted fabric having courses extending across the seam width and wales running lengthwise of the seam, each loop in said end edge portions being interlooped with an individual loop of said narrow fabric and no wale of the narrow

fabric being interknit with edge loops at opposite sides of the seam.

17. In knitted hosiery fabric, portions each having an edge formed of terminal wale loops, and knitted yarn joining the loops of one of said fabric portions to the loops of another of said fabric portions, at least a substantial part of said knitted yarn having regular courses and wales with the wales parallel to said edges and interknit with said edge loops, wherein the knitted yarn comprises at least two wales and one of said wales is interknit with loops in one of the end portions, and the other of said wales is interknit with edge loops opposite the folded end portion loops.

18. Knitted fabric having a knitted seam, said seam comprising edges of the fabric united by yarn knitted into courses and wales.

19. A stocking comprising fabric having opposite edge portions, and yarn knitted into connected courses and wales and interlooped with said opposite edge portions to form a knitted seam therefor.

20. A full-fashioned stocking comprising flat knit fabric formed of wales and courses and having opposite edge portions, and yarn knitted into wales and courses and interknitted with said opposite edge portions to form a knitted seam.

21. A full-fashioned stocking comprising flat knit fabric formed of wales and courses and having opposite edge portions, and yarn knitted into wales and courses and interknitted with said opposite edge portions to form a knitted seam, said yarn wales extending longitudinally of said seam.

22. A full-fashioned stocking comprising flat knit fabric formed of wales and courses and having opposite edge portions, and yarn knitted into wales and courses and interknitted with said opposite edge portions to form a knitted seam, certain of said yarn wales being interknitted with one of said opposite edge portions and certain other of said yarn wales being interknitted with the other of said opposite edge portions.

23. A full-fashioned stocking of flat knit fabric having opposite edges united by yarn to form a seam therefor, said yarn being knitted into loop formation, a plurality of loops of said yarn being interknitted with one of said edges and a plurality of other loops of said yarn being interknitted with the other of said edges, at least a substantial number of said interknitted loops being interknitted with only a single edge.

24. A full-fashioned stocking of flat knit fabric having the bottom edges of the heel portion joined by knitted yarn to form a heel seam for the stocking, said knitted yarn having a plurality of its loops interknitted with only one of said bottom edges and having a plurality of other loops interknitted with only the other of said bottom edges.

10 25. A knitted fabric having a knitted seam, said seam comprising at least the edge wale loops of two opposite fabric edge portions and a seaming yarn knitted to form wales and interlooped with wale loops in both of said fabric edge portions, at least one of said seaming yarn wales for at least 15 a part of its length being interlooped with only one of said fabric edge portions.

26. A stocking comprising heel fabric, the opposite edges of said fabric meeting at the bottom of the stocking heel, and yarn knitted into connected courses and wales and interlooped with at least certain opposite edge portions of said fabric to form a seam therefor.

27. A stocking comprising foot fabric, opposite edges of said fabric meeting at the heel of the stocking foot, and yarn knitted into connected courses and wales and interlooped with at least certain opposite heel edge portions of said fabric to form a seam therefor.

28. Knitted fabric having a knitted seam, said 30 seam comprising at least two fabric edges united together by means of seaming yarn, said yarn being in the form of fabric having knitted courses and wales and being interlooped with said edges.

29. Knitted fabric having a knitted seam, said 35 seam comprising at least two fabric edges interlooped with seaming yarn, said yarn being knitted and forming a plurality of courses and at least two wales.

30. Knitted fabric having a knitted seam, said 40 seam comprising at least two fabric edges interlooped with seaming yarn, said yarn being knitted and forming a plurality of courses and wales.

31. A seam structure in a full-fashioned flat knit stocking formed of courses of wales having opposite edge portions, said seam structure comprising narrow fabric of regular courses and wales, certain of said narrow fabric wales being interknitted with certain wales forming one of said edge portions and certain other of said narrow fabric wales being interknitted with certain wales forming the other of said edge portions.

JOSEPH L. BEERS.
